FOREIGN PATENT DOCUMENTS

WO 2013112325 A1 8/2013

Primary Examiner — Shannon W Morgan*Assistant Examiner* — Altaira J Swangin(74) *Attorney, Agent, or Firm* — The Law Firm of Andrea Hence Evans, LLC(57) **CLAIM**

The ornamental design for a pillow and blanket ensemble, as shown and described.

DESCRIPTION

FIG. 1 is a top, front left perspective view of a pillow and blanket ensemble;

FIG. 2 is a front view of the pillow and blanket ensemble design of FIG. 1;

FIG. 3 is a rear view of the pillow and blanket ensemble design of FIG. 1;

FIG. 4 is a left side view of the pillow and blanket ensemble design of FIG. 1;

FIG. 5 is a right side view of the pillow and blanket ensemble design of FIG. 1;

FIG. 6 is a top view of the pillow and blanket ensemble design of FIG. 1;

FIG. 7 is a bottom view of the pillow and blanket ensemble design of FIG. 1; and,

FIG. 8 is a view of the pillow and blanket ensemble of FIG. 1 in an alternate, folded configuration.

The broken lines shown in the figures depict portions of the pillow and blanket ensemble which form no part of the claimed design.

1 Claim, 6 Drawing Sheets(56)
